UNITED STATES PATENT OFFICE.

THOMAS GILBERT, OF LONDON, ENGLAND.

SIGHT FOR SMALL FIRE-ARMS.

SPECIFICATION forming part of Letters Patent No. 289,081, dated November 27, 1883.

Application filed December 23, 1882. (No model.) Patented in England May 11, 1882, No. 2,215; in France June 15, 1882, No. 149,581; in Germany June 18, 1882, No. 20,433, and in Italy June 30, 1882, XVI, 14,366, XXVIII, 397.

To all whom it may concern:

Be it known that I, THOMAS GILBERT, a subject of the Queen of Great Britain, residing at London, England, have invented new 5 and useful Improvements in Sights for Small Fire-Arms, (for which I have obtained a patent in Great Britain, No. 2,215, bearing date the 11th May, 1882, and sealed the 11th August, 1882,) of which the following is a specification.

This invention relates to further improvements in the improved sight for fire-arms for which Letters Patent were granted to me, No. 267,418, dated the 14th day of November, 15 1882.

The improved sight described in the specification of my said former Letters Patent was specially suitable for use with shotguns; and the present improvements have reference to 20 a slight modification in the construction of the sight, as therein described, and also to certain modifications whereby the sight is rendered specially applicable for ball fire-arms, and also for revolvers.

25 In order to enable my invention to be better understood, I will proceed to describe the same by reference to the accompanying drawings, in which—

Figure 1 is a plan, and Figs. 2 and 3 side 30 elevations, of a sight constructed according to my present improvements, showing the construction of sight I have found most advantageous for shotguns; Figs. 4, 5, and 6, similar views of the form of sight I have found 35 most advantageous for use with rifles or other ball fire-arms, and Fig. 7 shows a plan of a sight suitable for revolvers. The several figures are drawn about full size.

The sight shown in Figs. 1, 2, and 3 is constructed substantially the same as that shown 40 in the specification of my said former Letters Patent, except that it is formed with only three notches, *c*, which is the number I have found to answer best in practice, the notch 45 nearest the breech being now cut with small saw-like teeth. In these views, also, only one

piece of platinum, *d*, is shown fixed on the end of the center notch, as I have found in practice that one of such pieces is generally sufficient. This piece or center *d* may be 50 made of either platinum, silver, ivory, or enamel, and the notch on which the center is placed is rounded, as shown, so that the said center will be entirely out of the sight of the left eye.

55 The sight shown in Figs. 4, 5, and 6 is constructed substantially in the same manner as that hereinbefore described, and shown in Figs. 1, 2, and 3, except that it is of a pyramidal form, the right-hand side thereof being 60 cut with saw-like teeth or notches, with a groove or recess, *e*, in the middle thereof, at the end of which is placed the piece of platinum *d*. Although this sight is best suited for rifles and other ball-arms, it may also be 65 used for shotguns, and in either case with or without platinum.

For revolvers the sight may be made reversible, as shown in plan at Fig. 7, by forming the fore part of the right side with notches 70 in the reverse direction, and in addition to the notches on the breech end, the sight would be fixed on a central pivot (or a groove) at *f*, so that it could be turned to suit either the right or left eye, according to whether the revolver 75 be held in the right or left hand, as will be understood without further description. My improved sights may also be made of ivory, in which case I stain the sides of the notches black, leaving the ends opposite the 80 sight-eye white, or partly white and partly black. The use of the saw-like teeth is to prevent a glancing-surface on the notched angle, which is presented to the vision of the right eye, and which gives the sight a solid attracting 85 substance to the right eye only. The glancing angle or side of the sight produces a practically-invisible effect to the vision of the left eye only. Under cover of this novel principle the notched part is hidden from the 90 left eye and at the same time exposed to the right eye.

Having thus described my invention and the manner of performing the same, what I claim is—

1. The improved sight for fire-arms herein described, having a series of notches, the front one of which is cut with a series of small saw-like teeth, substantially as shown and described.
2. The reversible sight, suitable for revolv-

ers, having the series of notches at each end, 10 and with a central pivot or groove, as and for the purposes set forth.

THOMAS GILBERT.
